CLAIM

The ornamental design for a tank locker as shown and described.

DESCRIPTION

FIG. 1 is a perspective view of a tank locker according to the present application.

FIG. 2 is a front view of the tank locker of FIG. 1.

FIG. 3 is a rear view of the tank locker of FIG. 1.

FIG. 4 is a right side view of the tank locker of FIG. 1.

FIG. 5 is a left side view of the tank locker of FIG. 1.

FIG. 6 is a top view of the tank locker of FIG. 1.

FIG. 7 is a bottom view of the tank locker of FIG. 1.

FIG. 8 is another perspective view of the tank locker according to the present application.

FIG. 9 is another perspective view of the tank locker according to the present application; and,

FIG. 10 is perspective view of the tank locker of FIG. 1. The broken lines in all views are for the purpose of illustrating environmental structure and form no part of the claimed design.

1 Claim, 9 Drawing Sheets
